UNITED STATES PATENT OFFICE.

HARRY M. RYDER, OF WILKINSBURG, PENNSYLVANIA, ASSIGNOR TO WESTINGHOUSE ELECTRIC & MANUFACTURING COMPANY, A CORPORATION OF PENNSYLVANIA.

THERMIONIC DEVICE.

Application filed June 25, 1921. Serial No. 480,303.

My invention relates to evacuated electric devices and more especially to the construction and arrangement of the electrodes employed in such devices.

5 In its broad aspect, the object of my invention is to provide an evacuated electric device which shall be of unusual simplicity in design and ruggedness of construction and which shall be of a higher operating efficiency than has heretofore been possible in such devices.

More specifically, one object of my invention is to provide a vacuum tube embodying an arrangement of electrodes wherein a cylindrical anode is disposed concentric with the axis of the tube and wherein a plurality of filaments are disposed in the lateral surface of a cylinder surrounding the anode and disposed in symmetrical relation thereto.

20 Another object of my invention is to provide a filament-supporting structure whereby the filaments will always be maintained in the proper relation to the anode and to the walls of the tube.

25 Still another object of my invention is to provide a filament-supporting structure of such character that the filaments may be connected in parallel and fed from bus bars constituting parts of the filament-supporting structure.

30 A further object of my invention is to provide means whereby the temperature of the filament supply conductors in the press may be reduced without lowering the filament-current input.

35 A still further object of my invention is to provide an external control electrode composed of a metallic gauze and disposed concentric with the axis of the tube.

40 According to my invention, I provide an elongated vacuum-tube device which includes a filament structure axially supported from one end of the tube and a cooperating anode symmetrically disposed with respect to the filament structure and supported from an opposite end of the tube. The filaments are disposed as longitudinal elements of a cylinder which lies between the containing walls of the tube and the anode and is symmetrically disposed with respect to both. A control electrode, which is preferably composed of a metallic gauze, is so disposed that its field of force is substantially parallel to the space-current path between the filaments and the cylindrical anode.

Other objects, as well as details of construction, whereby my invention may be utilized, will be apparent from the following description, taken in connection with the accompanying drawings, in which;

60 Fig. 1 is a front elevational view of a vacuum tube embodying my invention, a portion of the containing walls being broken away.

Fig. 2 is a section on the line II—II of Fig. 1.

65 Fig. 3 is a front elevational view of a vacuum-tube device similar to that of Fig. 1 but showing a modification in the filament-supporting structure and, in addition, means for preventing vibration of the free end of 70 the anode.

Figs. 4 and 5 are sections on lines IV—IV and V—V respectively, of Fig. 3, looking in the direction of the arrows.

75 Fig. 6 is a front elevational view of a vacuum-tube device which differs from that of Fig. 1 in the filament structure and in the arrangement of the supporting electrodes within the tube, and

Fig. 7 is a section on the line VII—VII 80 of Fig. 6.

Referring to the form of my invention illustrated in Figs. 1 and 2, I have shown a complete evacuated electric device in the form of an elongated tube 1 which has a 85 plurality of filaments 2 and a cooperating anode 3 disposed therein. An external electrode 4 preferably of metallic gauze is disposed immediately adjacent the containing walls of the tube 1 but not necessarily in 90 contact therewith.

The filaments 2, which are disposed as longitudinal elements of a right circular cylinder the axis of which is concentric with that of the tube 1, are supported by a pair 95 of rings or so-called "filament busses" 5 and 6. The rings 5 and 6 are composed of a conducting material so that the filaments 2 may be fed in parallel. The tension of the filaments 2 may be adjusted by means of springs 7. The rings 5 and 6 are supported by means of the conducting supports 8, 9 and 11, 12, respectively, which extend through the press 13 at one end of the tube 1 and are preferably disposed in different planes immediately adjacent the filaments 2.

100 The anode 3, which may be so constructed as to form the lateral surface of a right circular cylinder, is supported by means of supporting arms 14 and 15 which are im- 110

bedded in a press 16 that is disposed in the end of the tube 1 which is opposite to that supporting the filament structure. The supporting conductor 15 extends through the 5 press 16 to form a supply lead to the anode 3. The anode 3 is symmetrically disposed with respect to the filaments 2 and also with respect to the walls of the tube 1. The grid 4, which may be disposed either within or 10 without the containing walls of the tube 1, is symmetrically disposed with respect to the filaments 2 and also with respect to the anode 3.

Referring to Figs. 3, 4 and 5, the vacuum-tube device shown differs from that of Figs. 1 and 2 in the filament structure and in the addition of means for preventing the vibration of the free end of the anode 3.

In the modification just mentioned, the 20 filaments are divided into two groups supported at one end by a central ring 6' and at the other end by oppositely disposed end-rings 5'. The end-rings 5' are also connected in parallel by the supporting conductors 8 which also function as current leads to the ends of the filaments 2 that are supported by the annular rings 5'. The central ring 6' is carried by supporting conductors 11 and 12. One end of the anode 3 30 is supported by the arms 14 and 15, as in the embodiment shown in Fig. 1. The unsupported end of the anode 3 is prevented from vibrating by means of a pair of cross-arms 17 which are in contact with the inner surface 35 of the anode 3. The cross-arms 17 are supported by means of a supporting rod 18 embedded in the press 13.

In Figs. 6 and 7 is shown a further modification of the filament structure and the 40 arrangement of the filament and anode supports within the tube. In the modification just referred to, it will be noted that the ring 5'' is supported by means of a supporting conductor 19 having laterally disposed cross members 20, opposite ends of which are rigidly secured to the ring 5''. The supporting conductor 19 may be so disposed as to coincide with the axis of the tube and is supported by, and extends through 45 the press 13. The filament-supporting ring 6'' is carried by arms 11 and 12, as in Fig. 1. The filament leads 11 and 19 may be connected to a base 21 of any approved design.

The anode 3, instead of being supported 55 from an opposite end of the tube, as in the previous figures, is supported by rods 22 and 23 which are also embedded in the press 13. A lead 24 serves to connect the anode 3 with external circuits through a binding 60 post 25.

One advantage of the structural arrangement of electrodes embodying my invention is the resulting simplicity in design, ease of construction and cheapness of manufacture 65 which it affords.

Another advantage of a vacuum-tube device embodying my invention is its high operating efficiency when employed as an oscillator in any of the well known oscillator circuits. In the usual type of vacuum-tube oscillator, the operating efficiency has heretofore been approximately fifty per cent. In the tube embodying my invention, however, I have been able to obtain a maximum operating efficiency of eighty-eight per cent, 70 with an average of seventy per cent. As just stated, these relatively high efficiencies were obtained when employing my tube as an oscillator in well known oscillator systems.

The favorable operating characteristics of 80 the tube as an amplifier or oscillator result from the arrangement of the grid-shaped cathode in the space between the anode and the externally disposed auxiliary, or control electrode, thus securing to the external electrode a strong electrostatic controlling action 85 in the space between the cathode and the anode where the major part of the electron discharge takes place.

Still another advantage of my invention 90 resides in the fact that, by employing a plurality of electrical parallel supply conductors for the filament, I am enabled to reduce, very materially, the working temperature of the conductors where they pass through the 95 press. The maintenance of the relatively low temperatures of the filament supply conductors in the press is of especial importance in high-vacuum tubes by reason of the fact that there is a tendency for the 100 filament seal to leak when the filament conductors are unduly heated.

While I have described and illustrated several preferred embodiments of my invention, I do not wish to be restricted thereto, but I desire that only such restrictions shall be placed upon my invention as are set forth in the appended claims.

I claim as my invention:

1. An evacuated electric device having a 110 plurality of filaments disposed in a cylindrical surface, a co-operating anode disposed substantially symmetrically with respect to said cylindrical surface, said filaments being disposed between said anode and the containing walls of said device, and an external control electrode composed of a metal gauze disposed substantially concentric with the axis of said cylindrical surface.

2. In a vacuum tube, a plurality of rings, 120 a plurality of filaments supported by said rings, conducting supports for one of said rings, conducting supports for said remaining rings, said remaining rings being connected in parallel by said last-named conducting supports.

In testimony whereof, I have hereunto subscribed my name this 14th day of June, 1921.

HARRY M. RYDER.
